UNITED STATES PATENT OFFICE.

JOSEPH E. PHILIPPON, OF ST. EVARISTE DE FORSYTH, QUEBEC, CANADA.

PIPE-THAWING APPARATUS.

1,243,973.

Specification of Letters Patent. Patented Oct. 23, 1917.

Application filed March 18, 1916. Serial No. 85,129.

To all whom it may concern:

Be it known that I, JOSEPH E. PHILIPPON, a subject of the King of England, residing at St. Evariste de Forsyth, in the county of 5 Frontenac, in the Province of Quebec and Dominion of Canada, have invented certain new and useful Improvements in a Pipe-Thawing Apparatus, of which the following is a specification.

- 10 The present invention has relation to certain new and useful improvements in devices and apparatus for thawing water pipes and other conduits; and, as its primary object contemplates the provision of a simple, 15 compact and durable device of the above nature, which is constructed to be easily operable and which consists of but a few parts whereby it is not liable to get out of order.
- 20 Various other objects and advantages will become apparent during the continuance of the following description.

These objects are accomplished by such means as are shown in their preferred form, 25 in the accompanying drawings, described in the following specification and then more specifically pointed out in the appended claims.

In the accompanying drawings wherein 30 like characters designate like parts throughout the several views:

Fig. 1 is a view in side elevation showing my invention as in its actual practice.

Fig. 2 is a view in longitudinal section, 35 of the body stand and the hot water container.

Fig. 3 is a view in detail of improved valve means that are arranged in the hot water container, and

Fig. 4 is a fragmentary view, showing the connection with the pipe to be thawed in detail.

In the present embodiment, 10 designates a suitable base or socle that may consist of, 45 spaced supporting beams, as shown in Figs. 1 and 2, the said beams serving to support an upright stand or carrying structure 11, that is braced through the instrumentality of knee braces 12. Knee braces 12 may be connected at their respective terminal ends, as at 13 to the beams 10 and the stand 11, as illustrated. Stand 11 in the present embodiment consists of uprights 14, mounted at their lower ends on a transverse block 15, 50 and connected at their upper ends by means of a cross member 16. Between block 15

and cross member 16, I mount a hot water container 17 of novel construction, said container having a bearing 18 upon its under face to coact with a like bearing 19 on block 15, whereby it may be quickly and easily rotated; while cross member 16 carries a stationary cover portion 20 as at 21, in order to engage with the upper portion of container 17 in the manner illustrated in Fig. 2. 65 As illustrated in Fig. 1, container 17 carries a circumferential flange 22 at its lower end, whereby it may be utilized as a winding drum, such as will subsequently appear.

Block 15 is slotted horizontally as at 23, 70 said slot receiving an idler drum 24 which has its respective gudgeons 25 and 26 journaled in suitable apertures 27 and 28 in the block 15. The drum 24 is provided at suitable points with circumferential flanges 29, 75 and 30 so as to preclude dislodgment of the tubing that is wound thereon and to insure the efficient operation of the device in general.

Container 17, as well as the winding drum 80 24, may be constructed of sheet metal or other desired material, and since this construction is merely arbitrary, it is to be understood that I do not limit myself in any way to that form shown. In container 17, 85 mount a drum 31 by means of suitable brace members 32 which are fixed to container 17 as at 33, said drum having mounted therein suitable partitions 34 and 35 as clearly illustrated in Fig. 2. Partition 34 forms a suitable compartment which has communication with an outlet spout 36 and is provided with an ingress opening 37 normally closed by means of ball valve 38. In order to insure efficient operation of ball valve 38 and at 90 the same time prevent clogging of the ingress opening 37 by the collection of dirt and other foreign matter thereabout, I increase valve 38 in a screen housing 39. Partition 35 likewise forms a compartment which has 95 communication with the interior of the container 17 through wire mesh member 40 and said last mentioned partition is provided with an ingress opening 41 normally by closed ball valve 42; the latter also operating in a screen housing 43.

A cylinder 44 has communication at its lower end with the interior of drum 31 and has operating therein a plunger head 45, carried by extension rod 46. Extension rod 46 is passed through suitably aligned apertures 47 in cover 20 and cross member 16.

and has its upper end equipped with a bearing 48 as clearly shown in Fig. 1. Actuating lever 49 is pivotally connected at one end as at 50 to a bearing 51 that is fixed to cross member 16 while it also has pivotal connection at an intermediate point as at 52 with bearing 48 above referred to. Consequently, by properly manipulating the free end of actuating lever 48, movement 10 may be imparted to plunger head 45 and the operating of the ball valves accomplished. In other words, upon upward movement of plunger 45, ball valve 43 will become unseated so that water from container 17 will be drawn into drum 31 while upon downward movement of the plunger, the valve 43 will move into a closed position, while the valve 38 will be unseated to permit the water in the drum 31 to be 20 forced outwardly through spout 36.

I also provide in conjunction with that structure above described, suitable heating apparatus designated in its entirety by the numeral 53, said heating apparatus including a boiler 54. A conduit 55 connects boiler 54 with container 17 as shown in Fig. 1, while a tube 56 is connected with outlet spout 36 of drum 31 as at 57 and passed a suitable aperture 58 in the side 25 wall of the container and subsequently wound about the periphery of the container, as illustrated. A second conduit 59 connects boiler 54 with block 15, while a second tube 60 has one end portion passed 30 through one hollow gudgeon 25 of the drum 14 and is connected with conduit 59 as at 61. This last mentioned tube is passed 35 through an aperture 62 in drum 14 and may be subsequently wound about the drum in 40 the usual manner.

I further provide a casing 63 that is connected with the pipe to be thawed 64 as at 65, one end of said casing receiving one end of tube 66 and carrying means as shown at 67 to retain the same in place, while an extension 58 on the casing communicates with the end of tube 59 and carries means as shown at 66, whereby a tight connection may be made.

50 The operation of my invention is substantially as follows:

The water from boiler 54 flows upwardly through pipes or conduits 55 to container 17 and upon proper manipulation of actuating lever 49, the water from container 17 55 will be forced through drum 31 as aforesaid to tube 56. From tube 56 the heated water is passed into the pipe to be thawed and subsequently passes back through conduit 59 and tube 60 to the boiler. By rotating drum 24 tube 60 may be wound or 60 unwound thereon while by rotating container 17, tube 56 may be properly regulated.

65 From the foregoing, it is apparent that

the pipe acted upon will be quickly and easily thawed by means of my improved apparatus and it will also be apparent that the said apparatus may be conveniently moved from place to place and operated with the greatest of ease. In view of the fact, therefore, that the advantages and novel features of my invention appear to be apparent from the foregoing, further detail description is deemed unnecessary.

In reducing my invention to practice, I find that the form referred to herein as the most practical and preferred embodiment is the most efficient, but realizing that certain conditions will necessarily vary in concurrence with the adoption of my device, I desire to emphasize the fact that various minor changes in the details of construction and in the proportion of parts may be resorted to when required without sacrificing any of the advantages of my invention, as defined in the appended claims.

Having thus fully described my invention, what I claim as new and desire to secure by Letters Patent is:

1. In a device as aforesaid; a body structure including a rotatably mounted container, feeding means including a boiler, a conduit connecting said boiler and said container, conduit means having one end open to the interior of said container and adapted to be wound thereon, an idler drum carried by said body structure, conduit means to be wound upon said idler structure and other conduit means connecting said boiler and one end of said last mentioned conduit means.

2. In a device as aforesaid; a body structure including independently rotatable hollow winding drums, heating means including a boiler structure, conduits connecting said boiler structure and said drums, and other conduits in communication with said first mentioned conduits to be wound upon said drums.

3. In a device as aforesaid; a carrying structure, a container movably mounted on said carrying structure, pump means operating in said container, heating means including a boiler structure, a conduit connecting said boiler and said container, other conduit means open at one end to the interior of said container to be wound on said container, an idler drum revolvably mounted on said carrying structure, conduit means to be wound on said drums and having one end passed through one of the gudgeons thereof, and other conduit means connecting said boiler and one end of said last mentioned conduit means.

4. In a device as aforesaid; a base, a stand arranged on said base, a fluid receptacle revolvably mounted on said stand and having a cover stationary with respect to said stand; in combination with a tube to be wound on

said container and having one end communicating with the interior thereof, and pump means associated with said container to force the contents thereof through said tube.

5. In a device as aforesaid; a base, a stand arranged on said base, a container revolvably mounted in said stand and having a cover fixed with respect to said stand; in combination with a tube to be wound on said container and having one end open to the interior thereof, means to introduce fluid into said container, and means including a handle portion arranged exteriorly of said container to force the contents thereof through said

10 tube.

6. In a device as aforesaid; a connecting joint to be attached to the pipe to be thawed, heating means including a boiler structure, and conduit means to convey the fluid from

15 said boiler structure to said joint connection and return; in combination with means interposed between said heating structure

and said joint connection to take up the slack in the conduit means and to instigate the flow of fluid.

7. In a device as aforesaid; means for connection with the pipe to be thawed, heating means including a boiler structure, conduit means connecting said boiler structure and said joint connection to convey the fluid to

25

30 said joints and return the same to said boiler; in combination with a stand having a movable container through which the fluid passes, pump means associated with said container to instigate the flow of fluid, and

35

an idler drum revolvably mounted on said carrying structure to take up the slack in certain of said conduit means.

In testimony whereof I affix my signature in presence of two witnesses.

JOSEPH E. PHILIPPON.
